UNITED STATES PATENT OFFICE.

JOHN H. WILSON, OF PHILADELPHIA, PENNSYLVANIA.

DESIGN FOR CLOTHES-RACK.

40,413.

Specification for Design.

Patented Dec. 21, 1909.

Application filed August 22, 1908. Serial No. 449,883. Term of patent 14 years.

To all whom it may concern:

Be it known that I, JOHN H. WILSON, a citizen of the United States, residing at Philadelphia, in the county of Philadelphia and State of Pennsylvania, have invented a new, original, and ornamental Design for Clothes-Racks, of which the following is a specification, reference being had to the accompanying drawing, forming a part thereof.

The figure is a perspective view showing my new design.

I claim:

The ornamental design for a clothes rack, as shown.

JOHN H. WILSON.
